United States Patent Office.

RICHARD CADLE, OF SHAWNEETOWN, ILLINOIS.

Letters Patent No. 88,128, dated March 23, 1869.

IMPROVEMENT IN BLACKING-BOXES.

The Schedule referred to in these Letters Patent and making part of the same

To all whom it may concern:

Be it known that I, RICHARD CADLE, of Shawneetown, in the county of Gallatin, and State of Illinois, have invented a new and valuable Improvement in Blacking-Boxes; and I do hereby declare that the following is a full, clear, and exact description of construction and operation of the same, reference being had to the annexed drawings, making a part of this specification; and to the letters and figures of reference marked thereon.

Figures 1 and 2 of the drawings are sectional representations of the machine by which the improvement to the blacking-box is made;

Figure 3 is the bottom of a blacking-box, improved; and

Figure 4 is a detail.

My invention relates to boxes for holding blacking; and

It consists in constructing, or forming a series of spurs on the bottom of such box, for the purpose of causing it to sit firmly, while the blacking is being removed with a brush.

These spurs are formed by a novel process, and my invention consists not only in the spurs themselves, but also in the means by which they are made.

The letter A of the drawings represents the bottom of a blacking-box, upon which the letters c are small, sharp spurs.

When the box sits on a floor, bench, or carpet, these spurs pass into the same, and hold the box with great firmness, while the operator is making a solution of the blacking with a brush.

These spurs c are formed by the machine shown on figs. 1 and 2 of the drawings, operating as hereinafter mentioned.

Letter B represents the bottom of my machine, and C are two upright posts or standards erected thereon.

Letter d is a block, forming the segment of a circle, fastened on the platform or bottom, on one side of the standards, and adapted to the size and shape of one side of a blacking-box. The inner sides of the standards C are cut out in a circular form.

Upon the bottom, A, and between the standards, is a circular block, or bed-piece, of the diameter of the

box, in which I form small holes, as shown on figs. 1 and 2, the number and size of which correspond to the number and size of the spurs I desire to form on the box-bottom. This block is marked D on the drawings.

The letter E represents a circular block, constructed in form shown, and having on its lower side a series of spurs, corresponding in number and proportions to the spurs I desire to make in the bottom of the box. This last-mentioned block must be made a little less in diameter than the diameter of the blacking-box, and its upper side must be grooved, or otherwise adapted to fit the lower end of the ratchet-post next mentioned.

Letter F is a ratchet-post, adjusted as shown, upon a cross-bar extending from one standard, C, to the other, and within a tubular post, G.

The letter H represents a coiled spring, attached to the ratchet-post F in the manner shown; and

Letter L is a ratchet-lever, pivoted in the tubular post G, the teeth of which mesh with and operate the teeth of the post F.

To operate my device, I place the bottom of the box upon the block D, after removing the cover. I then move the lever L forward with a rapid movement. This forces the spurs of block E into the bottom of the box, and the points therein, with which they come in contact, are pressed downward into the openings in the block D, thereby forming the spurs upon the bottom, as shown in fig. 3 of the drawings.

What I claim as my invention, and desire to secure by Letters Patent, is—

1. A blacking-box, constructed with spurs c on its bottom, substantially as and for the purposes specified.

2. The combination and arrangement of the block E, with its spurs, as described, with the block D and standards C, when the same are constructed as specified, and operated by suitable power, for the purpose of forming the spurs c, on the bottom of the box.

In testimony that I claim the above, I have hereunto subscribed my name, in the presence of two witnesses.

RICHARD CADLE.
